UNITED STATES PATENT OFFICE.

FRANK S. BOYDEN, OF CHICAGO, ILLINOIS.

DESIGN FOR A BROOCH.

40,349.

Specification for Design.

Patented Nov. 16, 1909.

Application filed October 19, 1908. Serial No. 458,574. Term of patent 7 years.

To all whom it may concern:

Be it known that I, FRANK S. BOYDEN, a citizen of the United States, residing at Chicago, in the county of Cook and State of Illinois, have invented a new, original, and ornamental Design for Brooches, of which the following is a specification, reference being had to the accompanying drawing, forming part thereof.

The figure is a plan view of a brooch showing my new design.

I claim:

The ornamental design for a brooch, as shown.

FRANK S. BOYDEN.
